UNITED STATES PATENT OFFICE.

EDWARD CRAIG, OF ST. JOSEPH, MICHIGAN, ASSIGNOR TO SARANAC AUTOMATIC MACHINE CORPORATION, OF BENTON HARBOR, MICHIGAN, A CORPORATION OF DELAWARE.

BASKET-MAKING MACHINE.

Application filed August 15, 1927. Serial No. 212,861.

This invention relates to the manufacture of baskets, and more particularly to the manufacture of bushel baskets of the kind that has a substantially flat bottom and that has inside and outside hoops at the top and bottom of the basket.

Generally stated, the object of the invention is to provide improved machinery whereby a basket of this kind is made by first fabricating the bottom unit, by attaching the sheet material to the upper edge of the inside bottom hoop, and by thereafter assembling staves around the periphery of the preformed bottom unit, and stapling or otherwise fastening the staves and the outside bottom hoop to the hoop of the preformed bottom unit, and securing the other hoops in place to form a basket which is tapered downwardly, which has a flat top and a flat bottom.

It is also an object to provide certain details and features of construction tending to increase the general efficiency and the desirability of basket making machinery of this particular character.

To these and other useful ends the invention consists in the matters hereinafter set forth and claimed, and shown in the accompanying drawings, in which,—

Fig. 1 is a side elevation, partly in vertical section, of portions of a machine embodying the principles of the invention.

Fig. 2 is an enlarged vertical section of the form upon which the basket is made, showing the basket upside down and in vertical section.

Fig. 3 is a plan view of the auxiliary form that is detachably supported on top of the main basket form.

Fig. 4 is a vertical section on line 4—4 in Fig. 3.

Fig. 5 is an enlarged, fragmentary, horizontal section of one side portion of the basket form, showing the method of assembling the staves, in dotted lines, around the outside of the form.

Fig. 6 is a plan view of the preformed bottom unit of the basket, showing the auxiliary form in dotted lines.

Fig. 7 is a side elevation of the basket, upside down, in the position in which it is preferably assembled and fastened together, showing the left-hand side thereof in vertical section.

As thus illustrated, the machine comprises a basket form 1, which is mounted to rotate about a vertically disposed axis. This form tapers upwardly, so the basket is made upside down. The lower part of the form has a flanged ring 2, and the middle of the form has a ring 3, as shown. The sides of the form are provided with stave holders 4 spaced apart a distance to position the staves and allow the staves to overlap each other a distance. The top hoop 5 of the basket is first placed in position on the form, against the ring 2, and the preformed bottom unit, comprising the inside bottom hoop 6 and the crossed slats 7, spaced apart as shown in Fig. 6 of the drawings, is then placed upside down on the top of the form. Then the auxiliary form 8 is placed on top of the preformed bottom unit, this auxiliary form being disk like and having its annular periphery shaped to fit snugly within the hoop 6 of the preformed bottom unit. Positioning pins 9 are provided on the bottom of the auxiliary form, to extend through the openings in the preformed bottom unit, and the lower ends of these pins engage the holes 10, it will be seen, in the top wall of the main basket form. The staves are then assembled on the form where they are temporarily retained in the proper position for fastening by the holders 4, and the outside hoop strips 11, 12 and 13 are placed in position and wound around the basket and stapled thereto, by means of staples 14, 15 and 16, or nails, or any other fastening devices can be used for this purpose.

Preferably the staves and hoops are secured together by staples, as shown, and for this purpose the machine is provided with staples 17, 18 and 19, of any suitable character, and operated in any suitable or desired manner, to insert the staples through the basket materials. The basket form is rotated intermittently, it will be understood, by any suitable or desired means, until all the staples are driven, the basket being stationary during such staple-inserting operation. In other words, three staples are inserted simultaneously, through the top and bottom and middle hoops of the basket, and during this operation the basket and the form are stationary; but as soon as these staples are driven, the basket is then partially rotated a distance to receive the next

set of staples. As stapling mechanism of this kind is old and well known, no further description thereof is necessary.

Thus, it will be seen that the method of 5 making the basket involves the making of the preformed bottom unit first, by stapling or otherwise securing the strips of sheet material 7 to the top edge of the inside bottom hoop 6, and after this the basket is then fab- 10 ricated around the said preformed bottom unit. This can be done by hand, but machinery is preferable, in view of the fact that staples are preferable to nails for commercial purposes. The staplers are, there- 15 fore provided with hoop guides 20, 21 and 22 to receive the hoop strips which are formed into the outside hoops 11, 12 and 13, these outside hoop strips being gradually bent around the basket as the latter rotates, 20 being fastened thereto by the driving of the staples in the manner shown and described. Thus only the one set of staples 16 is necessary, for securing both the inside and outside bottom hoops in place, and to secure the 25 staves 23 to the hoops, preferably in overlapped relation, whereby the basket has practically straight and downwardly tapering side walls, a flat bottom and a flat top. The bottom is springy and resilient and 30 forms a bottom cushion for the basket, to cushion the load therein. The inner ends of the staples 14 and 15 are clinched on the rings 2, 3, while the inner ends of the staples 16 are clinched on the annular periphery of 35 the auxiliary form 8.

What I claim as my invention is:

1. In a machine for assembling basket bodies comprising hoops and staves with preformed dished bottom units consisting of 40 hoops having the basket bottom forming materials secured to one edge thereof, comprising a support for the constituent parts of the basket body, a member fitting within the hoop of the preformed dished bottom and 45 adapted to abut one end of the support to retain the bottom in position for the fastening operation with the bottom forming material thereof disposed between said member and said support, whereby the fastening 50 of staves and hoops to the preformed bottom serves to produce a basket in which the bottom forming material is spaced from the corresponding end of the completed basket, and means for inter-connecting said support and member for rotation together.

2. In a machine for assembling basket bodies comprising hoops and staves with pre- 55 formed dished bottom units consisting of hoops having the basket bottom forming materials secured to one edge thereof, comprising a support for the constituent parts of the basket body, and a cylindrical member adapted to fit within the circular hoop of the preformed dished bottom and having

means to interlock with said support to 65 clamp the bottom forming material between said member and said support so that said member, said support and said bottom unit may rotate together, whereby the fastening of staves and hoops to the preformed bot- 70 tom serves to produce a basket in which the bottom forming material is spaced from the corresponding end of the completed basket.

3. In a machine for assembling basket bodies comprising hoops and staves with pre- 75 formed dished bottom units consisting of hoops having the basket bottom forming materials secured to one edge thereof, comprising an apertured frusto conical drum for receiving and supporting the constituent 80 parts of the basket body, a member fitting within the hoop of the preformed dished bottom unit and having a stud thereon adapted to project into said aperture, to interlock said member and drum for rotation, 85 and to clamp said bottom forming material between said member and drum, and fastening means for securing staves and hoops to the preformed bottom to produce a conical basket in which the bottom forming material is spaced from the corresponding end of the completed basket.

4. In a machine for assembling basket bodies comprising hoops and staves with preformed dished bottom units consisting of 90 hoops having the basket bottom forming materials secured to one edge thereof, comprising a support for the constituent parts of the basket body, and a freely movable member fitting within the hoop of the preformed 95 dished bottom and adapted to be seated on one end of the support to retain the bottom in position for the fastening operation with the bottom forming material thereof disposed between said member and said support, said member and preformed bottom being supported in operative position solely by said support, and means associated with said member and support for preventing accidental relative displacement thereof, 100 whereby the fastening of staves and hoops to the preformed bottom serves to produce a basket in which the bottom forming material is spaced from the corresponding end of the completed basket.

5. In a machine for assembling basket bodies comprising hoops and staves with preformed dished bottom units consisting of 105 hoops having the basket bottom forming materials secured to one edge thereof, comprising a support for the constituent parts of the basket body, a freely movable member fitting within the hoop of the preformed dished bottom and adapted to be seated on one end of the support to retain the bottom 110 in position for the fastening operation with the bottom forming material thereof disposed between said member and said sup- 115

port, said member and preformed bottom being supported in operative position solely by said support, whereby the fastening of staves and hoops to the preformed bottom ¹⁰ 5 serves to produce a basket in which the bottom forming material is spaced from the corresponding end of the completed basket, and means projecting through said preformed bottom and serving to connect said support and said member to prevent accidental relative displacement thereof.

Specification signed this 10th day of August, 1927.

EDWARD CRAIG.
